Specification for Design.

Patented Aug. 11, 1914.

Application filed August 21, 1913. Serial No. 786,042. Term of patent 7 years.

To all whom it may concern:

Be it known that I, WILL T. STEWART, a citizen of the United States, residing at Opelousas, in the parish of St. Landry and State of Louisiana, have invented a new, original, and ornamental Design for Key-Wrench, Bottle-Cap Opener, and Key-Rings, of which the following is a specification, reference being had to the accompanying drawings, forming part thereof, in which similar characters of reference indicate corresponding parts in the several views.

Figure 1 is a front view of a key ring and bottle opener showing my new design, Fig.

2 is a side view of the same, Fig. 3 is a sectional view on line 2—2 of Fig. 1 and Fig. 4 is a view looking from bottom to wider part at top.

I claim—

The ornamental design for a key wrench, bottle cap opener and key ring, as shown.

In testimony whereof I have signed my name to this specification in the presence of two subscribing witnesses.

WILL T. STEWART.
